UNITED STATES PATENT OFFICE

2,370,579

MANUFACTURE OF SUCCINIC ACID

Elton B. Punnett, Buffalo, N. Y., assignor to Allied Chemical & Dye Corporation, New York, N. Y., a corporation of New York

No Drawing. Application September 30, 1942,
Serial No. 460,327

11 Claims. (Cl. 260—537)

This invention relates to a process for the manufacture of succinic acid. It relates more particularly to the manufacture of succinic acid from fumaric acid.

Fumaric acid is obtained as a by-product in the manufacture of other organic products. For example, it is recovered as a by-product in the manufacture of maleic anhydride. Accordingly it provides an accessible source for the manufacture of succinic acid; but owing to its low solubility in water, it has not been employed for this purpose.

It has been proposed heretofore to manufacture succinic acid by reacting salts of fumaric acid in aqueous solution with hydrogen in the presence of a hydrogenation catalyst. Such processes, however, require the preparation of a hydrogenation catalyst and use of special pressure equipment for efficient operation, and involve the inconvenience and explosion hazards attendant upon manipulation of gaseous hydrogen under pressure.

It has also been proposed by E. E. Reid in U. S. P. 2,141,406 to manufacture succinic acid by reacting maleic acid in aqueous solution with the metals standing between hydrogen and the alkaline earth metals in the E. M. F. series. This process requires the use of maleic acid, and while it would be possible to first convert fumaric acid to maleic acid as a preliminary step to the production of succinic acid, such a procedure would be uneconomical and difficult to carry out.

It is the principal object of the present invention to provide a process for the manufacture of succinic acid from fumaric acid which is simple to carry out, convenient to operate, and which produces succinic acid directly from fumaric acid while avoiding the disadvantages inherent in the known processes.

Other objects of the invention will in part be obvious and will in part appear hereinafter.

I have discovered that when fumaric acid, suspended in an aqueous medium, is treated with certain metals and certain acids, succinic acid is produced in satisfactory yields for commercial application.

Thus I have discovered that succinic acid can be produced by adding any one or more of the metals zinc, aluminum, chromium, tin and magnesium to an aqueous suspension of fumaric acid, followed by the addition of a non-oxidizing acid which is capable of reacting with the metal to liberate hydrogen and which is sufficiently stronger than succinic acid to liberate succinic acid from a succinate of such metal.

This result is surprising in view of the low solubility of fumaric acid in water and in view of the disclosure in the Reid Patent 2,141,406 that, in the process of the patent for making succinic acid from maleic acid, fumaric acid is produced as an undesired by-product in the course of the reaction of certain metals with aqueous solutions of maleic acid.

In the practice of the process of the present invention in accordance with one method of procedure, fumaric acid is suspended in water and one of the metals above mentioned is added to the suspension, preferably in a highly reactive form. A reaction occurs with evolution of heat. Upon completion of the addition of the metal, a non-oxidizing acid of the type referred to above is added to the reaction mixture, preferably while maintaining the reaction mixture at an elevated temperature which for convenience does not exceed the boiling point of the reaction mixture. When the reduction has been completed, the succinic acid is recovered from the resulting reaction mixture. Ordinarily this is accomplished by removing from the hot solution of succinic acid, resulting from the reaction, insoluble material which may be present therein (for example, unreacted metal, unreduced fumaric acid, salts formed in the reaction, etc.), cooling the resulting clarified solution to effect crystallization of succinic acid, and separating the succinic acid crystals from the mother liquor.

Preferably the temperature conditions, concentrations, choice and nature of reagents and the manner of their incorporation are controlled with a view to securing a maximum yield under conditions of economical operation. Thus, the fumaric acid is suspended in an amount of water which is approximately just enough to form, at the elevated temperatures employed, a saturated solution of the succinic acid produced; so that upon completion of the reduction, succinic acid may be recovered in economical amounts by direct crystallization from the resulting solution, preferably after separation of insoluble contaminants when present. In general from about 2 to about 4 parts by weight of water per part of fumaric acid fulfill this condition.

The metal is preferably employed in a form adapted to react advantageously with the fumaric acid; such as a form presenting an extended surface accessible to the liquid portion of the reaction mixture. For instance, the metal may be best employed in finely divided form, e. g., in the form of powder. Thus, zinc is preferably employed in the form of zinc dust in view of the

greater activity thereof. The amount of metal used is advantageously approximately the amount theoretically required to reduce the amount of fumaric acid employed to succinic acid. In the interest of economy and in order to produce high yields of succinic acid, the quantity of metal employed is preferably slightly in excess of that theoretically required to reduce the fumaric acid to succinic acid. An excess, for instance, of about 5% over the theoretically required amount has been found suitable.

Of the metals found suitable for the reaction of the invention enumerated above, it has been found that zinc and aluminum produce the highest yields of succinic acid based on the weight of fumaric acid initially employed for the process. These metals are therefore preferred.

The acids which are suitable for the reaction are water-soluble non-oxidizing acids, strong enough to liberate succinic acid from a succinate of the metal employed for the reduction. In general suitable acids are those which are at least as strong as formic acid, e. g., having a dissociation constant of at least $10^{-3.7}$ at about 25° C. Examples of such acids are formic, chloracetic, malic, citric, oxalic, phosphoric, sulfuric and hydrochloric acids. Those acids which form water-soluble salts of the metal employed in the reduction are in general preferred. Strong acids such as sulfuric acid and hydrochloric acid are especially suitable. The acid is advantageously employed in approximately the amount theoretically required for complete reaction with the amount of metal used. Preferably it is slightly more than the chemical equivalent of the amount of metal used for the reaction; for instance, an excess of about 5% has been found desirable.

In general, the reaction is carried out at an elevated temperature. For simplicity of operation, avoiding use of pressure or reflux apparatus, temperatures between about 85° C. and the boiling point of the reaction mixture are employed.

Thus, in the preferred practice of the present invention, fumaric acid is suspended in an amount of water approximately equal to that required to form, at about 85° C., a saturated solution of an equivalent amount of succinic acid, and zinc or aluminum in finely divided form is added to the agitated suspension in portions, while maintaining the temperature at 85° to 90° C. Before use, the metal is assayed for its reduction activity (i. e., its equivalence to hydrogen which it can generate with mineral acid) and an amount of the metal is used which is necessary theoretically to generate about 2.1 atoms of nascent hydrogen per molecule of fumaric acid used. (It is noted, if the reduction activity of the metal is found to be less than 100%, a proportionately larger amount of the metal is used.) After all the metal has been added, the mixture is agitated, and the acid to be used is added in portions at such a rate that excessive or substantial liberation of free hydrogen is avoided, while maintaining the temperature below the boiling point of the mixture. After addition of the acid, the temperature is maintained at the desired level until the reaction is substantially complete. The hot aqueous solution is separated, e. g., by filtration, from the water-insoluble constituents of the reaction mixture (including, for example, unreacted metal, and in some cases unreduced fumaric acid and insoluble salts of the metal used for the reduction) and the succinic acid

contained in the aqueous portion of the reaction mixture is then recovered by any suitable procedure. For instance, if the solution is sufficiently concentrated or saturated with reference to succinic acid, the latter may be crystallized by cooling, and separated from the mother liquor in substantially pure form, e. g., by filtration or centrifuging.

The invention will be more readily understood from the following examples, in which parts are by weight and temperatures are expressed in degrees centigrade.

Example 1.—348 parts (3 mols) of crude fumaric acid, obtained as a by-product of the manufacture of maleic anhydride from benzene by catalytic oxidation, are slurried with 852 parts of water, and 207 parts (3.17 mols) of zinc dust are added portion-wise. An exothermic reaction occurs and the temperature rises. The rate of addition of metal is controlled to maintain the temperature at about 90°, with external cooling if necessary. After all of the zinc dust has been added, 358 parts (3.4 mols) of 66° Bé. sulfuric acid are added at such a rate that substantially no hydrogen gas is evolved, while maintaining the temperature between about 85° and about 90°. The addition of the acid ordinarily requires about two hours. To the resulting mixture, 8 parts of decolorizing charcoal (e. g., "Darco," "Norit," etc.) are added, and the mixture is heated with agitation for about one hour at a temperature of about 95° to about 100°. The reaction mixture is then filtered while hot, and the filtrate is cooled to a temperature between about 20° and about 25°. Succinic acid, which crystallizes from the filtrate, is separated by filtration or centrifuging from the mother liquor. The crystalline mass is washed successively with 5 portions of water of 200 parts each, and the washed crystalline mass is dried in an atmospheric drier at about 100°. The dry succinic acid recovered contains about 98.9% succinic acid, 0.5% fumaric acid, and 0.13% ash, and is substantially free from heavy metals.

Yields equivalent to about 90% of theory based on the total amount of fumaric acid employed have been obtained by this procedure. The wash water may be used in making up the fumaric acid slurry for subsequent reductions, thereby avoiding loss of the succinic acid contained therein.

Example 2.—348 parts (3 mols) of purified fumaric acid are suspended in 1200 parts of water and 57 parts (2.11 mols) of powdered aluminum are added to the mixture at such a rate that the temperature does not rise substantially above 85°. 358 parts (3.4 mols) of 66° Bé. sulfuric acid are introduced while maintaining the temperature of the mixture at 85° to 90°, the addition of the acid requiring approximately two hours. The resulting mixture is heated for about one hour to a temperature between 95° and 100° and is then filtered. The filter cake consists mainly of unreacted aluminum. Upon cooling the filtrate to about 25°, a slurry of succinic acid crystals is obtained. The slurry is filtered, and the crystalline filter cake is washed and dried as in the preceding example.

The product thus recovered contains 95% succinic acid and 4.6% fumaric acid.

Example 3.—To a slurry of 348 parts (3 mols) of purified fumaric acid, suspended in 1200 parts of water, 110 parts of powdered chromium (2.11 mols) are added at such a rate that the temperature does not rise above about 85°. The mixture is then heated to boiling and 358 parts of 66°

Bé. sulfuric acid are added drop-wise. An exceedingly vigorous reaction takes place. Upon completion of the reaction, the mixture is worked up in the same manner as in the preceding example. A crystalline product containing 92.4% succinic acid and 7.5% fumaric acid is obtained.

It has been found that chromium does not react appreciably at temperatures below about 97° while above this temperature the reaction tends to become exceedingly violent. As a result, the yield of succinic acid obtained is lower than in the preceding examples.

Example 4.—Fumaric acid is reduced to succinic acid by the method employed in Example 2 but substituting 377 parts (3.17 mols) of powdered tin for the aluminum used in said example, and an amount of hydrochloric acid equivalent to the sulfuric acid employed in said example. The crystalline product recovered contains 66.7% succinic acid and 32.1% fumaric acid.

Example 5.—A slurry of fumaric acid is reduced by the process of Example 2 but substituting 77 parts (3.17 mols) of magnesium chips and turnings for the powdered aluminum used in said example. On working up the reaction mixture by the procedure of Example 2, a crystalline mass containing about 50% succinic acid and 50% fumaric acid is obtained.

Example 6.—A chemically equivalent quantity of hydrochloric acid is substituted for the sulfuric acid used in the procedure of Example 5. The crystalline product obtained in this case contains about 45% succinic acid and about 55% fumaric acid.

In Examples 5 and 6, relatively lower yields of succinic acid are obtained as compared with Examples 1 and 2, apparently as a result of the excessive reactivity of the magnesium, whereby control of the liberation of hydrogen is rendered relatively difficult, resulting in losses of hydrogen.

Example 7.—A slurry of fumaric acid is reduced with zinc dust in the manner described in Example 1, substituting an equivalent amount of formic acid for the sulfuric acid employed in said example. Upon working up the reaction mixture by the procedure set forth in Example 1, a crystalline product containing 61% succinic acid, 2.5% fumaric acid, and 22.5% zinc (in the form of its salts) is obtained. The filter cake separated from the hot reaction mixture in the course of the clarification thereof consists mainly of unreacted zinc together with a small amount of succinic acid and fumaric acid.

Example 8.—Fumaric acid is reduced with zinc dust in the manner described in Example 1, but substituting an equivalent amount of monochloroacetic acid for the sulfuric acid used in said example. Upon filtration of the hot reaction mixture no filter cake is obtained, and the crystalline product recovered upon cooling the filtered solution contains 91% succinic acid and 9% fumaric acid.

Example 9.—Fumaric acid is reduced with zinc dust as described in Example 1, but substituting an equivalent amount of malic acid for the sulfuric acid employed in said example. The results are similar to those obtained in the preceding example.

Example 10.—An aqueous slurry of fumaric acid is reduced with active zinc in the manner described in Example 1, substituting an equivalent amount of phosphoric acid for the sulfuric acid used in said example. Upon filtration of the hot reaction mixture, a filter cake consisting mainly of unreacted zinc and insoluble zinc phos-

phates is separated. The crystalline product recovered from the filtrate contains 70% succinic acid and 30% fumaric acid.

Example 11.—Fumaric acid is reduced by a process similar to that of Example 1, substituting an equivalent amount of oxalic acid for the sulfuric acid used in said example. The filter cake obtained upon filtration of the hot reaction mixture contains unreacted zinc and insoluble zinc oxalate. The crystalline product recovered from the filtrate contains about 96% succinic acid and about 4% fumaric acid.

Example 12.—Fumaric acid is reduced with zinc dust in a procedure similar to that of the preceding example, substituting an equivalent amount of citric acid for the oxalic acid used in said example. The filter cake obtained upon filtration of the hot reaction mixture consists almost entirely of zinc citrate, and the crystalline product recovered upon cooling the filtrate contains 85% succinic acid and 15% fumaric acid.

The best yields are obtained by using powdered zinc or aluminum with a strong non-oxidizing mineral acid, particularly sulfuric acid. Relatively lower yields are obtained in the case of magnesium, apparently as the result of the greater reactivity of this metal, compared with zinc and aluminum. In the case of tin, yields are lower apparently as the result of the lower reactivity of this metal under the above reaction conditions; while with chromium relatively low yields appear to be due to the peculiar sensitivity of this metal under the conditions of the reaction to the temperature employed. Thus, zinc and aluminum appear to possess the optimum degree of reactivity, especially for use with the preferred mineral acids and under the preferred operating conditions.

The use of acids which are weaker than sulfuric acid, while effective for the purposes of the reaction, results in relatively lower yields of succinic acid. Formic acid used in Example 7 is effective for the reduction, but is not strong enough to eliminate the metal completely from the crystalline product recovered. Thus, in order to obtain succinic acid substantially uncontaminated with salts thereof, it is desirable to use acids stronger than formic acid. Strong mineral acids are preferred. Phosphoric, oxalic and citric acids generally produce insoluble salts of the metals employed for the reduction; hence for preferred operation they are not employed in the interest of technical convenience.

Variations and modifications may be made within the scope of this invention; hence, the details of the foregoing examples are to be interpreted in an illustrative rather than a limiting sense.

I claim:

1. A process for the manufacture of succinic acid, which comprises mixing fumaric acid in an aqueous medium with a metal selected from the class consisting of zinc, aluminum, chromium, tin, and magnesium, and adding to the resulting mixture a non-oxidizing acid which is capable of reacting with the metal to liberate hydrogen and which is sufficiently stronger than succinic acid to liberate the latter from a succinate of the metal, said non-oxidizing acid being added in at least the amount theoretically required to react with the amount of metal employed.

2. A process for the manufacture of succinic acid, which comprises mixing an aqueous suspension of fumaric acid with a metal selected from the class consisting of zinc, aluminum, chromium,

tin, and magnesium, in a form presenting an extended surface accessible to the reaction mixture, and adding to the resulting mixture a non-oxidizing acid which is capable of reacting with the metal to liberate hydrogen and which has a dissociation constant of at least $10^{-3.7}$ at 25° C., said non-oxidizing acid being added in at least the amount theoretically required to react with the amount of metal employed.

3. A process for the manufacture of succinic acid, which comprises mixing fumaric acid in an aqueous medium with a finely divided metal selected from the class consisting of zinc, aluminum, chromium, tin, and magnesium, at least in the amount theoretically required for the reduction of the fumaric acid and adding to the resulting mixture a strong non-oxidizing mineral acid adapted to form a water-soluble salt of the metal employed for the reduction, said non-oxidizing acid being added in at least the amount theoretically required to react with the amount of metal employed.

4. A process for the manufacture of succinic acid, which comprises mixing a finely divided metal selected from the class consisting of zinc, aluminum, chromium, tin, and magnesium, with an aqueous suspension of fumaric acid, and then adding to the resulting mixture a non-oxidizing acid which is capable of reacting with the metal to liberate hydrogen, said non-oxidizing acid being added in at least the amount theoretically required to react with the amount of metal employed, and at such a rate as to avoid substantial liberation of hydrogen gas.

5. A process for the manufacture of succinic acid, which comprises mixing an aqueous suspension of fumaric acid with a finely divided metal selected from the class consisting of zinc, aluminum, chromium, tin, and magnesium, at a temperature of about 85° C. to the boiling point of the mixture, and adding to the resulting mixture a non-oxidizing acid which is capable of reacting with the metal to liberate hydrogen, said non-oxidizing acid being added in at least the amount theoretically required to react with the amount of metal employed.

6. A process for the manufacture of succinic acid, which comprises adding to an aqueous suspension of fumaric acid a finely divided metal selected from the group consisting of zinc, aluminum, chromium, tin, and magnesium, in approximately the amount theoretically required to reduce the fumaric acid to succinic acid, adding to the resulting mixture a non-oxidizing acid which is capable of reacting with the metal to liberate hydrogen and which is sufficiently stronger than succinic acid to liberate the latter from a succinate of the metal, in approximately the amount theoretically required to react with the amount of metal employed, while maintaining a temperature of 85° C. to the boiling point of the reaction mixture, and recovering succinic acid from the resulting reaction mixture.

7. A process for the manufacture of succinic acid, which comprises adding zinc to an aqueous suspension of fumaric acid, adding a non-oxidizing mineral acid to the resulting mixture in at

least the amount theoretically required to react with the amount of zinc employed while maintaining a temperature of 85° C. to the boiling point of the reaction mixture, and recovering succinic acid from the resulting reaction mixture.

8. A process for the manufacture of succinic acid, which comprises mixing fumaric acid in an aqueous medium with finely divided zinc, adding a non-oxidizing acid at least as strong as formic acid to the resulting mixture, and controlling the rate of said addition and the temperature of the reaction mixture so as to avoid substantial liberation of hydrogen gas.

9. A process for the manufacture of succinic acid, which comprises adding to an aqueous slurry of fumaric acid finely divided zinc in an amount slightly in excess of that theoretically required to reduce the fumaric acid to succinic acid, then adding a quantity of sulfuric acid to the resulting mixture in an amount slightly in excess of the chemical equivalent of the zinc employed while maintaining the temperature within the range from 85° to 90° C., controlling the rate of addition of said acid so as to avoid substantial liberation of hydrogen gas, heating the reaction mixture to a temperature of 95° C. to 100° C. to complete the reduction, clarifying the aqueous portion of the reaction mixture, cooling said clarified aqueous portion to effect crystallization of succinic acid, and separating the crystallized succinic acid from the mother liquor, the amount of water present in said reaction mixture being just enough to form a substantially saturated solution of the succinic acid produced.

10. A process for the manufacture of succinic acid, which comprises adding aluminum to an aqueous suspension of fumaric acid, adding a non-oxidizing mineral acid to the resulting mixture in at least the amount theoretically required to react with the amount of aluminum employed while maintaining a temperature of 85° C. to the boiling point of the reaction mixture, and recovering succinic acid from the resulting reaction mixture.

11. A process for the manufacture of succinic acid, which comprises adding to an aqueous slurry of fumaric acid finely divided aluminum in an amount slightly in excess of that theoretically required to reduce the fumaric acid to succinic acid, then adding a quantity of sulfuric acid to the resulting mixture in an amount slightly in excess of the chemical equivalent of the aluminum employed while maintaining the temperature within the range from 85° to 90° C., controlling the rate of addition of said acid so as to avoid substantial liberation of hydrogen gas, heating the reaction mixture to a temperature of 95° to 100° C. to complete the reduction, clarifying the aqueous portion of the reaction mixture, cooling said clarified aqueous portion to effect crystallization of succinic acid, and separating the crystallized succinic acid from the mother liquor, the amount of water present in said reaction mixture being just enough to form a substantially saturated solution of the succinic acid produced.

ELTON B. PUNNETT.
